UNITED STATES PATENT OFFICE.

CLARENCE B. WILTSE AND WILLIAM J. SMITH, OF MOUNT KISCO, NEW YORK.

SHUTTER-HINGE.

1,280,611.

Specification of Letters Patent.

Patented Oct. 1, 1918.

Application filed November 14, 1917. Serial No. 201,990.

To all whom it may concern:

Be it known that we, CLARENCE B. WILTSE and WILLIAM J. SMITH, citizens of the United States, residing at Mount Kisco, in the county of Westchester and State of New York, have invented certain new and useful Improvements in Shutter-Hinges, of which the following is a specification.

This invention relates to hinges, designed 10 most especially for shutters and like swinging parts required to be held in open position against closing by currents of air.

The invention provides a hinge which prevents the casual unhinging of the shutter or 15 like part and which admits of locking the shutter in open position.

A further purpose of the invention is the provision of means for strengthening and bracing the hinge and which co-operates 20 with the locking means to insure positive action thereof and the formation of a hinge which is durable and efficient.

Other objects and advantages may become 25 apparent to persons who read the following details of description in connection with the accompanying drawings in which:

Figure 1 is an elevation of a fragment of 30 a window frame and shutter connected by a hinge of well known construction and having my attachment secured thereon.

Fig. 2 is a vertical sectional view taken on the line 2—2 of Fig. 1, and Fig. 3 is a horizontal sectional view taken on the line 3—3 of Fig. 1.

Referring to these drawings in detail, in 35 which similar reference characters correspond with similar parts throughout the several views, the window frame is designated by the letter A; the window shutter B; the 40 stationary section of the hinge C, and the movable section of the hinge D. As previously stated, these elements A, B, C, and D, are of well known construction, and will not be described in detail.

The pintle (not shown) of the hinge is 45 removed and replaced by the special pintle 10 which holds the hinge elements C and D in their original relation to one another except that they are spaced apart by means 50 of a horizontal plate 11 and a washer or disk 12. However, the disk 12 is only subsidiary for lessening the friction between the hinge members C and D, and therefore, the hinge member D may be considered as 55 resting immediately upon the plate 11. This plate 11 is apertured at 13 and receives the

pintle 10, and a screw 14 passes through an aperture in an upturned ear 15 and engages with the window frame A so as to coöperate with the pintle and extension C' of the lower 60 hinge member for supporting the plate 11 in its horizontal position. The plate 11 is provided with an upwardly curved flange 16, the upper curved surface of which consists of a cam which coöperates with an extension D' of the hinge member D and with a reinforcing arm or plate 17 for holding the shutter hinge in its open and closed positions, as hereinafter more fully explained. The extension D' has one end formed into 65 a bearing through which the pintle 10 extends, while the arm 17 has one end curved around this bearing, as shown at 18; and the reinforcing arm 17 is secured by a screw 19 to the hinge member D. 70

A second reinforcing member consists of a horizontal portion 20 and an apertured vertical portion 21 which latter is provided with an opening through which a screw 22 extends into the shutter B. The horizontal 80 portion 20 is provided with an aperture 23 through which the pintle 10 extends. 75

Studs 24 are provided at opposite sides of the top end of the pintle 10, and a cam lever 25 is pivotally mounted upon these 85 studs. A washer 26 may be provided between the cam 27 and the horizontal element 20, but, as in the case of the washer 12, this washer can also be eliminated, and the cam 27 may operate in direct contact 90 with the element 20 so that when the cam lever 25 is swung into its broken line position, the hinge member D is held against upward movement with relation to the plate 11, so that the cam or flange 16 constitutes a 95 stop for preventing the arms 17 and D' from swinging over the cam 16. However, when the lever 25 is in its vertical or full line position, the swinging of the hinge member D over the cam 16 causes the elements 17 and 100 18 to rise as they pass over the cam 16, thereby raising the pintle 10 against the tension of a spring washer 28, which latter may also constitute a nut-locking device, in coöperation with a washer 29, for preventing accidental turning of a nut 30 which is in screw-threaded engagement with the lower end of the pintle 10; it being understood that the washer 29 is non-rotatably mounted on 105 pintle 10. However, my invention is not 110 limited to this particular form of nut lock. It will be seen that the device may be ten-

sioned by rotating the nut 30, thereby increasing or diminishing the bearing of the nut against the spring washer 28.

In operating this device, the shutter may 5 be opened in the usual way, thereby moving the elements 17 and D' over the cam 16. When these elements have moved from one end to the other of said cam, the weight of the shutter and the tension of the spring 10 washer 28 move the shutter down to its normal position. Movement of the shutter to its open position widens the gap between the frame A and shutter B sufficiently to allow the lever 25 to be swung through said gap 15 into the broken line position shown in Fig. 1; thereby blocking the elements 17 and D' against being raised so that the cam 16 now acts as a stop for preventing the shutter from being moved into its closed position so 20 long as the lever 25 remains in its horizontal position; but when said lever is raised, the shutter may be closed as shown in the foregoing.

Although I have described this device in 25 minute detail, it is to be understood that my invention is not limited to this specific construction and arrangement of parts, but my invention is susceptible of such changes that do not constitute a departure from the inventive idea disclosed in the following 30 claims.

What I claim as my invention is:

1. The combination with a pair of hinge members, of a pintle pivotally connecting 35 said hinge members, a plate provided with an aperture through which said pintle extends, said plate being interposed between said hinge members and in fixed relation to one of the latter, means on said plate for 40 coöperation with the elements of the other hinge member for locking said hinge members against relative movement around said pintle, and means coöperative with said pintle for rendering the first said means effective and ineffective.

2. The combination with hinge members 45 of ordinary construction, of a pintle pivotally connecting said hinge members, a cam

lever pivotally connected to said pintle, an apertured plate provided with a cam and being disposed between said hinge members and having said pintle through its aperture, and means for holding said plate in stationary relation to one of said hinge members and in such relation to the other of said hinge members that the latter is slidable over said cam when the hinge is being opened or closed, and means on said pintle and being coöperative with said cam lever for locking said hinge members against relative movement along said pintle, whereby said cam acts as a stop for preventing relative movement of said hinge members around said pintle.

3. In combination, a pair of hinge members, a movable pintle connecting the hinge members, a plate disposed between the hinge members and apertured to receive the pintle, a cam on the plate for co-acting with the relatively movable hinge member, a second 70 plate beyond the hinge members and having one of the hinge members disposed between it and the plate disposed between the hinge members, and a cam lever mounted on the pintle and co-acting with said second plate 75 to confine the movable hinge member between the two plates.

4. In combination, a fixed hinge member, a fixed plate, a cam on the fixed plate, a movable hinge member, a reinforcing arm secured at one end to the movable hinge member and having its opposite end receiving the eye portion of said movable hinge member, a plate movable with the movable hinge member and having the latter between it and the fixed plate, a pintle passing through the hinge members and both plates and reinforcing arm, and a cam lever pivoted to the pintle and co-acting with the movable plate.

In testimony whereof we affix our signatures in presence of two witnesses.

CLARENCE B. WILTSE.

WILLIAM J. SMITH.
